UNITED STATES PATENT OFFICE.

EDWARD J. CONDON, OF NEW YORK, N. Y., ASSIGNEE OF ONE-THIRD TO ELEAZER I. RAINS
AND ONE-THIRD TO GEORGE W. RUPPERT, BOTH OF NEW YORK, N. Y.

ELECTRICAL WATER-HEATER.

No. 884,367.

Specification of Letters Patent. Patented April 14, 1908.

Application filed June 8, 1907. Serial No. 377,850.

To all whom it may concern:

Be it known that I, EDWARD J. CONDON, a citizen of the United States, residing in the borough of Manhattan, of the city of New York, in the State of New York, have invented certain new and useful Improvements in Electrical Water-Heaters, of which the following is a specification, reference being had to the accompanying drawings, forming part hereof.

This invention relates to electrical water heaters of the general character of that shown and described in Letters Patent of the United States No. 861,811, dated July 30, 1907, and it has for its general object to improve the construction and operation of such heaters as will be more fully explained hereinafter.

The special objects of the invention are to improve the construction and arrangement of the means for supporting and connecting the pipes through which the electrical heating current and the water to be heated flow with a view to securing the greatest efficiency of the apparatus, preventing the possibility of short circuiting of the electrical current across parts of the apparatus, and reducing the liability to breakage of the parts as well as to the grounding of the electrical current or other results of breakage, to improve the mechanical construction of the apparatus, and to improve the apparatus in other respects as will be pointed out.

The invention is illustrated in the accompanying drawings as embodied in a convenient form of apparatus and in said drawings—

Figure 1 is a view in elevation, with the outer casing and the main operating shaft in section, of the improved apparatus. Fig. 2 is a section on the plane indicated by the broken line 2—2 of Fig. 1. Fig. 3 is a section on the plane indicated by the broken line 3—3 of Fig. 1. Fig. 4 is a detail section on the plane indicated by the line 4—4 of Fig. 2. Fig. 5 is a detail section on the plane indicated by the broken line 5—5 of Fig. 3. Fig. 6 is a top view of the controlling switch, on a larger scale. Fig. 7 is a detail view partly in section and partly in elevation illustrating a modified embodiment of the invention. Fig. 8 is a detail view, on a larger scale, of one of the bushings shown in Fig. 7.

In the embodiment of the invention illustrated in Fig. 1 of the drawings, the apparatus comprises a suitable base *a*, which is

preferably rectangular and incloses the controlling mechanism hereinafter described, and an outer shell or casing *b* which is erected upon the base *a* and incloses and protects the heating tubes. In this form of the apparatus there is provided a main body *c* of porcelain or other suitable nonconducting material, having extended through it a plurality of longitudinal chambers *c'* which form tubes for the passage of water to be heated. Disks *c''* are held against the ends of the body *c*, as by a discharge pipe *c'''* provided with nuts and washers *c''*. The caps or disks *c''* serve to support the conducting tubes *d*, as hereinafter described, and to provide connection, both for the electrical current and for the water, from one conducting tube to another as well as connection from one chamber or tube *c'* to another. A packing *c⁵* is interposed between the main body *c* and the cap or disk *c''* at each end to prevent leakage of water and to confine it to its intended course. The conducting tubes *d* are somewhat longer than the body *c*, projecting beyond the same at the ends, and are seated in sleeves *c⁶* which are preferably molded in the porcelain or other nonconducting material. Within each sleeve is a bushing *c⁷*, preferably threaded into the sleeve and forming a tight joint with the end of the conducting tube, a lead washer *c⁸* being preferably interposed between the tube and the bushing. The bushing has one or more ports, as at *c⁹*, establishing communication between the central bore of the bushing and a channel *c¹⁰* which may be formed about the same. A plug *c¹¹* is threaded into the outer end of the sleeve *c⁶* to make a tight joint and prevent the leakage of water at this point, a lead or other washer or packing *c¹²* being interposed, if necessary. The sleeves *c⁶* are united in pairs, alternately at opposite ends of the body *c*, by other sleeves *c¹³*, for which seats are formed in the caps or blocks *c''*, the corresponding ports *c¹⁴* of the sleeves *c⁶* being connected by the sleeve *c¹³* so that a continuous channel for the water is formed from one tube *d* to the next in series. A channel *c¹⁴* in the cap or block *c''*, also affords communication from one chamber or tube *c'* to the next in order. It will be understood that the connections between the tubes *d* and the chambers *c'* in the bottom block or cap *c''* are effected in the same manner as in the top cap or block *c''* so that no further description or

illustration is required. The tubes are connected at the top and at the bottom in alternation and the last tube d of the series terminates within the tube or chamber c' and the latter is not connected at the corresponding end to the next tube or chamber c' . As shown in Fig. 5 the last tube or chamber c' of the series communicates through a channel c^{16} in the lower block c^2 and a port c^{18} within the outlet tube c^2 . A continuous channel for the water is thus formed from the inlet c^{17} through the conducting and heating tubes d in succession and through the chambers c' in succession to the outlet pipe c^3 . The pipes d are heated by the electric current which is conducted to them, as hereinafter described, and as the water moves in contact with the interior and the exterior of each tube it is quickly heated and the maximum efficiency of the electric current employed is realized. As indicated by dotted lines at d' , in Figs. 4 and 5, ports might be formed in the tubes d to communicate with the chambers c' so that the water may flow in the same direction through and outside of the tubes d , instead of flowing first through all of the tubes d in series and then through all of the chambers c' in series. It will be understood that the plugs c^{11} are accessible from outside of the caps or blocks c^2 so that each bushing c^7 can be adjusted to make a tight joint with the corresponding tube d . The sleeve c^3 which connects the two sleeves c^6 is threaded into said sleeves and as all joints are thus threaded joints, not only can tight connections be made but there is no danger of creating leaks by melting out solder as would be the case if the connections were made by soldering.

The water to be heated is supplied from a suitable source through a pipe e which is directly connected, as by a pipe e^3 , with the inlet c^{17} through which water is admitted to the heating element, and there is also provided a by-pass e^4 by which water may be supplied directly to the outlet pipe c^3 without passing through the heating pipes. As fully described in said application for Letters Patent, the main supply pipe e^3 and the by-pass e^4 are controlled by valves which are operated from a single handle in such a manner that the water which first flows from the outlet c^3 is at or near the normal temperature of the water supplied to the heater and is then gradually raised in temperature until the highest temperature is reached, all of this being effected by movement of the controlling handle from its initial point in one direction. The construction of the valves by which this result is accomplished may be the same as that shown in said application for Letters Patent of the United States and need not be further described herein.

The spindles f^7 and g^6 of the two valves are provided respectively with gears h' and h^2 which are engaged by a common intermediate gear h provided with a controlling handle h^3 applied to its shaft h^4 (see Figs. 1 and 6). The movement of the handle h^3 from its initial position in one direction effects the opening of both valves and the continued movement of the handle closes the by-pass valve until the flow of water through the by-pass valve alone is opened so that the water flows from the outlet pipe c^3 without being heated.

The electrical connections for supplying current to the conducting and heating tubes d of carbon or other suitable material are similar to those described in said application for Letters Patent, but differ in some details as will now be described. These connections are controlled manually by the movements of the controlling handle h^3 and also automatically by the flow of water to the heating tubes. The controlling means are so arranged that no current flows when both valves are closed and so that a switch is closed immediately after the movement of the controlling handle h^3 to open the valve in the pipe e^3 has commenced, the circuit through the heater being completed automatically as soon as the flow of water to the heating tubes has assumed some volume.

As shown in Fig. 1 of the drawings connection with one side of the main supply circuit is made at k and thence by binding post k' to one member k^2 of a snap switch, the other member k^3 of which is connected by wire k^4 with an automatic circuit closer at m , which is substantially the same as that shown in said application for Letters Patent. From the other side of the automatic circuit closer m connection is made by wire k^5 with the first of the series of tubes d . The current passes through the tubes d in succession, causing them to become highly heated in its passage, and from the last one of the tubes d the circuit is completed as by wire k^6 to the battery or other source of current. The switch k^2 , k^3 is arranged to be closed quickly on proper movement of the controlling handle h^3 . For this purpose the shaft h^4 carries a hub h^5 upon which is loosely mounted an operating lever h^6 , a spring h^7 being also mounted on the hub h^5 to hold the lever h^6 in operative position but permitting it to yield. On the spindle k^7 of the switch is mounted a lever k^8 with which the operating lever h^6 is arranged to coöperate. The member k^3 of the switch is pivoted upon the spindle k^7 and is provided with two stops k^9 and k^{10} between which the lever k^8 is free to swing. A spring k^{11} has its ends connected respectively to the member k^2 of the switch and the lever k^8 . The parts are properly related in position, as shown in Fig. 6, so that when they

65 provided respectively with gears h' and h^2

are in the position indicated by full lines the spring k^1 holds the switch open. As the controlling handle h^3 is moved over to the left the operating lever h^6 engages the lever k^8 and swings it to the dotted line position, in which movement the spring k^{11} is carried over the center of oscillation and therefore acts upon the switch member k^2 to snap the same into contact with the switch member k^3 . In the continued movement of the handle h^3 after the switch has been closed the operating lever h^6 yields and slips by the end of the lever k^8 , being immediately restored to proper position to engage the lever k^8 in the return movement of the handle h^3 , during which movement the switch is snapped open as soon as the spring k^{11} is carried beyond the center.

The automatic circuit closer, the position of which is indicated at m in Fig. 1, is arranged substantially as set forth in said application for Letters Patent to be operated automatically by the current of water flowing through the pipe e^8 , so that the electrical current of the heating tubes shall not be completed until the flow of water has commenced.

In the embodiment of the invention shown in Fig. 1 all of the outer tubes or chambers c' are formed in the one body c of porcelain or other suitable insulating material, but obviously each tube d might be surrounded by a separate tube of porcelain or other suitable insulating or nonconducting material, as indicated at c^{20} in Fig. 7. In this construction the caps or blocks c^2 have molded therein sleeves o which are threaded to receive stuffing boxes o' by which tight joints are made with the outer tubes c^{20} . A second sleeve o^2 , also molded in the block or cap c^2 , is extended through the sleeve o and is slotted at its extremity to form spacing fingers by which the tube d is centered with respect to the tube c^{20} ; the slots between the fingers affording passage for water. A bushing o^3 having an enlarged end o^4 which is threaded for engagement with the sleeve o^2 and a slightly less enlarged end o^5 , slotted, as at o^6 , to permit free passage of the water and provided with holes o^7 for the same purpose, is screwed into the sleeve o^2 against the end of the tube d , to establish electrical connection between the tube and the sleeve o^2 , a lead washer o^8 being interposed between the end of the bushing and the end of the tube if necessary to insure contact. A plug o^9 is screwed into the sleeve o^2 against the end of the bushing o^3 , with interposed packing o^{10} to seal the joint. A channel is provided from each sleeve o^2 to the next of the series in order, at one end or the other of the tubes, and electrical connection is at the same time established, by a sleeve o^{11} which is threaded at its ends into the corresponding sleeves o^2 . Ports d^2 are formed in the tubes d to permit

the flow of the water outside of the tubes as well as through them. Water connections and electrical connections are provided in this construction substantially as previously described with respect to the construction shown in Fig. 1 and the operation is the same as in the case of the construction shown in Fig. 1, the water, however, flowing through and outside of each of the tubes d in series from one to another.

In the improved construction shown and described herein, whether in one form or another, it will be seen that the employment of a threaded coupling or connection between the conducting tubes enables the use of solder to be dispensed with and therefore avoids the danger of melting out the solder by the passage of the electrical current, with the consequent creation of leaks, besides permitting close contact and tight joints to be made. Furthermore, as each conducting and heating tube is inclosed in a separate chamber, whether such separate chambers are formed by separate tubes or in a common body, the danger of shunting of the electrical current from one terminal to another is avoided, as well as the danger of short circuiting by accidental contact of one tube with another or by breakage of a tube. For the same reason, also, the electrical current can not be grounded on the base or outer casing or other part of the apparatus and the danger from this source is therefore avoided. Should any tube break it can be removed readily and replaced by another.

It will be understood that various changes in details of construction and arrangement can be made and that the invention, therefore, is not restricted to the precise construction shown and described herein.

I claim as my invention:

1. An electrical water heater comprising a plurality of chambers having walls of insulating material and adapted to permit the passage of water therethrough, conducting and heating pipes within said chambers respectively and also adapted for the passage of water therethrough, and means to supply electrical current to said conducting and heating pipes.

2. An electrical water heater comprising a plurality of chambers having nonconducting walls and adapted for the passage of water therethrough and communicating one with another in series, conducting and heating pipes disposed within said chambers and also adapted for the passage of water therethrough and connected one with another in series, and means to supply electrical current to said conducting and heating pipes.

3. An electrical water heater comprising a body of insulating material having formed therein a plurality of chambers adapted for the passage of water therethrough, conducting and heating pipes centrally placed in said

- chambers respectively and also adapted for the passage of water therethrough, and means to supply electrical current to said conducting and heating pipes.
5. An electrical water heater comprising a body of insulating material having a plurality of chambers therein adapted for the passage of water therethrough communicating with another in series, conducting and heating pipes centrally placed in said chambers respectively and also adapted for the passage of water therethrough and connected one with another in series, and means to supply electrical current to said conducting and heating pipes.
5. An electrical water heater comprising a body of insulating material having a plurality of chambers adapted for the passage of water therethrough, conducting and heating pipes centrally placed in said chambers respectively and adapted for the passage of water therethrough, blocks or caps for the ends of said body of insulating material, couplings for connecting said conducting and heating tubes carried by said blocks or caps, means for securing said blocks or caps in position upon the ends of said body of insulating material and means to supply electrical current to said conducting and heating tubes.
30. 6. An electrical water heater comprising a plurality of conducting and heating tubes, connections for said tubes, each comprising two longitudinal sleeves and a transverse sleeve having screw threaded engagement with said longitudinal sleeves, and means to supply electrical current to said tubes.
35. 7. An electrical water heater comprising a plurality of conducting and heating tubes, connections for said tubes, each comprising two longitudinal sleeves, with a bushing and a screwed plug in each and a transverse sleeve having screw threaded engagement with said longitudinal sleeves, and means to supply electrical current to said tubes.
40. 8. An electrical water heater comprising a plurality of conducting and heating tubes, connections for said tubes, each comprising two longitudinal sleeves and a transverse sleeve having screw threaded engagement with said longitudinal sleeves, a block or cap of insulating material supporting said connections, and means to supply electrical current to said tubes.
5. An electrical water heater comprising a plurality of conducting and heating tubes, connections for said tubes, each comprising two longitudinal sleeves with a bushing and a screw plug in each and a transverse sleeve having screw threaded engagement with said longitudinal sleeves, blocks or caps in which said connections are seated at opposite ends of said tubes, and means to supply electrical current to said tubes.
10. An electrical water heater comprising conducting and heating tubes, valve controlled means to supply water thereto, an operating handle therefor, means to supply electrical current thereto, and a snap switch operated by the movement of said handle to open and close the electrical circuit.
15. An electrical water heater comprising conducting and heating tubes, valve controlled means to supply water thereto, an operating handle therefor, means to supply electrical current thereto, a snap switch in the circuit of said electrical current, a switch lever and an operating lever yieldingly carried with said operating handle and adapted to shift said switch lever in one direction or the other as it is moved with the operating handle.
20. 11. An electrical water heater comprising conducting and heating tubes, valve controlled means to supply water thereto, an operating handle therefor, means to supply electrical current thereto, a snap switch in the circuit of said electrical current, a switch lever and an operating lever yieldingly carried with said operating handle and adapted to shift said switch lever in one direction or the other as it is moved with the operating handle.
25. This specification signed and witnessed this 7th day of June, A. D., 1907.
